UNITED STATES PATENT OFFICE.

GEORGE F. GREEN, OF KALAMAZOO, MICHIGAN.

PHOTOGRAPHIC SHUTTER.

SPECIFICATION forming part of Letters Patent No. 432,999, dated July 29, 1890.

Application filed July 12, 1889. Serial No. 317,269. (No model.)

To all whom it may concern:

Be it known that I, GEORGE F. GREEN, of Kalamazoo, in the county of Kalamazoo, and the State of Michigan, have invented new and useful Improvements in Camera or Photographic Shutters; and I do hereby declare that the following is a full and accurate description of the same, reference being had to the accompanying drawings, wherein—

10 Figure 1 is a perspective view of my shutter. Fig. 2 is an elevation of the shutters separated. Fig. 3 is an elevation of the same together. Fig. 4 is a section in line with the axis of the aperture.

15 This shutter belongs to that class which has folding wings opening and closing by movements in opposite directions in parallel planes transverse to the axis of the lens.

The objects of my invention are, first, to cause each leaf of the shutter to open and close again by two movements in opposite directions impelled by a single rectilinear motion of the actuating-force; second, to open and close the shutter, as above, by motion on a pivot at 20 one side of the lens-aperture to produce a larger and longer exposure of one part of the picture than another; third, in the elastic cushions to receive the wings when they open to prevent noise and jar; fourth, in the lock, 25 whereby the wings are prevented from moving, except when desired, and, fifth, in a fibrous lining covering the inner face of the shutter-case to deaden sound and prevent leakage of light.

30 That others may fully understand my invention, I will particularly describe it.

A is the shutter case or frame, and B is the ordinary pneumatic engine for operating the shutter-wings. This engine is operated by 35 pneumatic pressure produced usually by compressing an elastic bulb, and thereby forcing air under pressure into the engine.

40 C and D are the wings of the shutter. They may be both mounted on the same pivot-pin e. Each of said wings includes rather more than one-half a circular disk, so that when they are closed together their adjoining edges will overlap each other and exclude light. The pivot-pin e being below the aperture, 45 the shutters move faster at the extremities of the wings over the far margin of said aperture than at the margin nearer said

50 pivot-pin, and therefore light will be admitted more abundantly on the far side than on the nearer side; and in mounting the shutter it is 55 so adjusted that the flood of light, or larger exposure, comes from foreground, and the lesser quantity from the sky. The object and effect of this are to equalize the illumination of the sensitive plate. I am aware that 60 attempts to accomplish this end have been made heretofore by openings of various shapes in sliding shutters; but such shutters are required to slide horizontally, and necessarily commence the exposure at one margin 65 and close it at the other, and therefore the beam of light moves across the plate, instead of beginning at a certain point, expanding therefrom, and quenching at the point of beginning, which is universally believed to be the 70 preferable mode.

The shutter-wings C D open by moving away from each other and close by moving toward each other, and this movement and counter-movement are produced by one continuous rectilinear movement of the engine.

75 The wing C is provided with a single curved slot f, having the concave side toward the pivot e; but it is so located as to said center that nearly the whole length of said slot extends toward that side of said pivot which is 80 toward the engine B. The pin g, attached to the piston of the engine B, projects through said slot and normally rests in the extremity thereof, and is in diameter sufficient to fill the 85 width of said slot. The pin g moves in a straight line, which is a chord of the curve of said slot, and therefore in moving along said line the edge of the slot will be engaged and the wing caused to move in a direction opposite to the motion of the pin. This is because 90 the pin acts as a cam pressing downward or laterally on the wing at points lateral as to the pivot, and said downward pressure continues until the pin reaches a point above and 95 nearest said pivot. After passing said nearest point the action of the pin will be an upward or outward lateral pressure, and the movement of the wing will therefore be reversed and move in the same direction as the pin g. As 100 a matter of convenience, the slot terminates at the point reached by the pin as it passes the pivot e, so that the reverse movement of the wing will be partly due to a direct thrust of

the pin at the end of said slot. The action, therefore, is partly that of a cam and partly that of a crank. When the pin *g* and the wing *C* come to rest, the pin is in the inner 5 end of the slot, which on the retrograde movement of the pin presents itself in the same relation to the pin, and therefore the wing is caused to repeat its movements, so that in whichever direction the pin moves the shutter has imparted to it the two motions above described.

The shutter *D*, having to be moved by the same pin and coincidentally with shutter *C*, but in opposite directions therefrom, requires 15 a different form of slot, because its first motion is in the same direction with the motion of the pin. The shutter *D* is therefore provided with a slot *h*, the outer extremity of which is nearly above the pivot-pin when the 20 shutter is closed. The outer half of said slot is curved with the concavity toward the pivot, but the inner half turns sharply upward. The pin *g* rests in the inner extremity of said slot when the shutters are closed, and at the 25 angle or midway when the shutter is fully open. Under these circumstances the advance of the pin *g* will act upon the upward portion *l* of said slot and push the shutter open, but cannot act upon any portion to 30 push it shut again while said pin continues to advance. I therefore attach to the piston a second pin *k*, which, moving in a line parallel with the movement of the pin *g*, but on the opposite side of the pivot *e*, presents itself in an opposite relation to the wing *D*. I 35 therefore place in the lower margin of the wing *D* a shoulder *n*, located so that when the pin *g* has advanced far enough to open said shutter the pin *k* will engage said shoulder and close the shutter again. Therefore 40 in causing the movements of the shutter *D* the action of the engine is partly that of a cam and partly that of a crank.

Because the wings of the shutter open and 45 close again by reciprocation and move with considerable rapidity, it is necessary to avoid jar and sound at the completion of the first or opening movement, and I therefore attach to the shutters pieces of india-rubber or other 50 suitable material *p*. For this purpose india-rubber is better than any other material, because of its great elasticity and power to absorb and neutralize concussion. No vibration from a blow delivered upon an india-rubber cushion will be transmitted to the 55 parts beyond. The pieces *p* of india-rubber pass through the shutter-case from side to side, and therefore extend across the space in which the shutter-wings move and admit of 60 no space between said india-rubber and the shutter-case, into which the wing may drive and be wedged fast.

When a time exposure is desired, an obstruction may be placed to arrest the piston 65 at the middle of its movement. This obstruction may be arranged in various ways. I have employed a pivoted stop *s* as a conven-

ient and efficient method. Its lever end may project through the front of the camera, so that the stop may be operated from without. 70 It is also desirable to provide some method of locking the wings to prevent them from moving when not desired. This is useful when the carrier is being moved from place to place, and in the class of small cameras which use 75 continuous sensitive films without slides, depending upon the exposing shutter for the exclusion of light; and I therefore provide a positive locking-pin *T*, arranged to pass through the shutter-blades. It is manifest 80 that many other forms of lock taking hold of both wings and holding them may be employed, and I therefore do not desire to be limited to the particular form shown.

My shutter may be placed in front of, between, or behind the lenses, as desired, and the form of the case or frame may be modified accordingly. The form shown in the drawings is intended to be placed behind the lens within the camera. When placed within the 90 camera, the mechanism is concealed and protected from injury, and light is more effectively excluded; but in the form shown in the drawings it may be attached to the front of the lens by the addition of a proper collar or 95 ring adapted to slip over the front end of the lens-tube. When placed within the camera, it is desirable to produce a close fit without trouble and without special workmanship, and it is also desirable to deaden all sounds 100 arising from the action of the moving parts. I therefore cover the back of the shutter-frame with a layer or coating of fibrous material *U*, which renders the shutter-frame self-adapting to the front of the camera and capable 105 of preventing leakage of light and the transmission of sound.

Having described my invention, I claim—

1. In a photographic shutter, two wings pivoted at one side of the aperture and the 110 overlapping edges fashioned to separate on a line through the axis of the lens, and thereafter to separate more rapidly at one side of said aperture than at the other side, combined with an engine adapted to open and close the 115 wings of said shutter by movements in opposite directions, as set forth, for the purpose of flooding the foreground with light, as set forth.

2. In a photographic shutter, two wings pivoted at one side of the aperture and respectively provided with slots *f* *h*, substantially as shown, combined with a pneumatic actuating-engine acting in said slots to cause said shutters to open and close by a single motion 125 of the engine, as set forth.

3. In a photographic shutter, two wings *C* and *D*, pivoted at *e* and respectively provided with slots *f* *h*, and the shoulder *n* on wing *D*, substantially as shown, combined with the 130 engine *B*, provided with pins *g* and *k*, moving in parallel straight lines to open and close the shutter by a single movement of said engine.

4. In a photographic shutter, reciprocating wings pivoted at one side of the aperture, an engine adapted by a single movement to open and close the shutter by movements in opposite directions, and a pivoted-stop *s*, adapted to be set so as to limit the motion of the piston, as set forth.
5. In a photographic shutter, the reciprocating wings, combined with a case which in- | closes said wings on both sides thereof, and ¹⁰ elastic buffers *p*, extending across the shutter-space and into the plates of the case on either side of the same.
